UNITED STATES PATENT OFFICE

109,217

DESIGN FOR AN APPARATUS FOR CHEMICAL ANALYSIS

Horry M. Jones, Chicago, Ill.

Application January 19, 1938, Serial No. 74,417

Term of patent 14 years

To all whom it may concern:

Be it known that I, Horry M. Jones, a citizen of the United States, residing at Chicago, in the county of Cook and State of Illinois, have invented a new, original, and ornamental Design for an Apparatus for Chemical Analysis, of which the following is a specification, reference being had to the accompanying drawing, forming a part thereof, in which

The figure is a front perspective view of an apparatus for chemical analysis showing my new design.

I claim:

The ornamental design for an apparatus for chemical analysis, as shown.

HORRY M. JONES.
